2 Claims. (Cl. 66—63)

This application is a division of my application
for United States patent, filed March 17th, 1934,
Serial No. 716,021, and has for its object a device
for protecting the latches of the latch needles in
flat pearl machines by means of resilient mem-
bers or brushes.

In the flat pearl machines, during the opera-
tion of which certain needles remain inoperative,
that is, assume a position of rest in the respective
needle bed guideways during any desired number
10 of traverses of the cam slide in dependency on
the knitted pattern to be produced, the throwing
over of the loops last formed frequently results
in an undesired jumping movement of the corre-
sponding needle latches to the effect that the lat-
ter are neither closed nor completely opened, so
that these latches must be closed prior to the
passage of the needles concerned underneath the
fixed needle jack check rail by action of this rail
20 or by a latch closing blade especially provided
for this purpose. In this way the needle latches
as well as the needle latch closing blades are worn
at certain parts or even damaged. This fact is
detrimental to the run of machines with a high
25 speed traversing movement of the needle cam
slide particularly during the production of tubu-
lar goods or the like.

According to the present invention, these draw-
backs are eliminated in the protecting device for
30 the needle latches of the needles of flat pearl ma-
chines by arranging in substitution for the usual
latch closing blades on the cam slide on both
sides of each needle cam box a resilient member
at each side of the needle bed behind the knock-
35 ing over edge of the needle beds above the latches
of the needles occupying their operative positions,
which resilient member closes any needle latches
that may still be open and which maintains the
closed latches depressed.

40 Admittedly, it is already known to provide ne-
edle latch closing means in fixed position for the
needle latches to ride against during the return
movement of the respective needles. It is also
45 known to use for opening the latches of needles
brushes which are provided with laterally off-
standing tufts for cleaning the opened needle
latches and the field of action of the needles.
Such arrangements are, however, neither adapt-
50 ed for closing needle latches that may have re-
mained still open or maintain the closed latches
depressed, in such manner, that the needle
latches are safeguarded against damaging, nor
were these arrangements originally intended for
55 this office, as provided according to this invention.

In the accompanying drawing a constructional
form of the invention is illustrated, in which

Fig. 1 shows a partial top plan view of a known
flat knitting machine to which the needle latch
protecting device according to the invention is
applied, and

Fig. 2 shows a section on the line II—II in
Fig. 1.

In these figures, it will be seen that above the
needle bed portions B₁ and B₂ provided with in-
10 inner edges about which the meshes are knocked
over needle latch opener brushes 4 and 4' of a
known type are secured to the needle cam boxes S
and S' of the needle cam box slide C, in a known
manner. The numeral 5 refers to needle jack
15 check rails. Above the needles the needle cam box
S composed of the cam portions 3 and 3' is ar-
ranged. At each side of the double needle bed
on the cam slide on both sides of the respective
needle cam box above the needles 1, which are
20 moved into operative position by means of the
correlated needle jacks 2, and immediately at the
sides of the latch opener brushes 4 and 4' behind
the respective knocking over edge for the meshes,
resilient members or brushes 6 and 6' provided
25 with bristles are arranged which members serve
for maintaining the needle latches closed. The
thus formed tufts of bristles 6, 6' are of a cross
section that may resemble the form of a narrow
rectangle disposed parallel to the longitudinal
30 plane of the machine, the bristles being inclined
to the needles at about the same angle as the
needle latch openers 4, 4'.

The operation of this protecting device is the
following:

When the needle cam box slide is traversed
across the needle bed in the direction of the arrow
Q (Fig. 1) and thus from left to right, the needles
1 assuming their working positions are advanced
in the respective guideways of the needle beds,
40 for producing hosiery, by action of the needle
cam box portions 3, and the latches of the needles
1 are opened by the leading latch opener brushes
4 whereby the needles with their latches in
opened position are passed under the jack check
45 rails 5 without, however, previously contacting
with these rails. Thereupon the needles are re-
tracted in the respective guideways of the needle
bed by action of the cam portions 3 and the loops
put on other needles, so that the needle latches
50 are closed.

Owing to the presence of the resilient members
6 and 6', it is feasible to move any needles with
their latches in closed condition, i. e. needles that
are in inoperative position, during the next fol-
55

lowing traverse of the cam slide from right to left, under the jack check rails 5 without requiring the latches of these needles to be previously closed or opened by means of these check rails. 5 By this means damaging of the needle latches as well as wear on the check rails is avoided during the traversing movements of the cam box slide in both directions, as simultaneously with the knitting operation being interrupted by the moving slide the latches of those needles that are present within the range of sinking the loops are maintained closed by the resilient needle protecting members 6 and 6'.

I do not limit myself to the particular size, 15 shape, number or arrangement of parts as shown and described, all of which may be varied without going beyond the scope of my invention as shown, described and claimed.

I claim:

20 1. In a safety device for latch needles in flat pearl machines, the combination with a double needle bed having inner edges for knocking over the meshes thereabout, latch needles slidably ar-

ranged in said needle bed and a needle cam box slide adapted to traverse said needle bed, of a resilient latch closer member arranged on said cam box slide at both ends of the needle cam boxes thereof adjacent the respective edge so as to close any latches or maintain depressed the closed latches of those needles which retain their loops without knitting during the formation of a course. 5

2. In a safety device for latch needles in flat 10 pearl machines, the combination with a double needle bed having inner edges for knocking over the meshes thereabout, latch needles slidably arranged in said needle bed and a needle cam box slide adapted to traverse said needle bed, of 15 flexible latch closer bristles arranged on said cam box slide at both ends of the needle cam boxes thereof adjacent the respective edge so as to close any latches or maintain depressed the closed 20 latches of those needles which retain their loops without knitting during the formation of a course.

HANS DIEM.
